UNITED STATES PATENT OFFICE.

GAVIN RALSTON AND EARL BLANKENSHIP, OF COMMERCE, OKLAHOMA.

ARTIFICIAL HAND.

1,304,201.

Specification of Letters Patent.

Patented May 20, 1919.

Application filed June 21, 1918. Serial No. 241,215.

To all whom it may concern:

Be it known that we, GAVIN RALSTON and EARL BLANKENSHIP, citizens of the United States, residing at Commerce, in the county 5 of Ottawa, State of Oklahoma, have invented certain new and useful Improvements in Artificial Hands; and we do hereby declare the following to be a full, clear, and exact description of the invention, such as will 10 enable others skilled in the art to which it appertains to make and use the same.

The present invention relates to new and useful improvements in artificial hands, more particularly of that general type 15 wherein the digits of the hand are formed by pliable core members disposed within the yielding finger body members whereby the finger members may be retained in any desired position upon being bent to such position.

It is in general the object of the present invention to improve the construction of devices of this character, more particularly with respect to effecting an increased 25 strength and durability thereof, and a more natural simulation of the natural hand.

A more detailed object resides in the provision of an improved means for anchoring the finger members to the body of the hand, 30 whereby to lessen breaking strain on the members and prevent a seam at their juncture with the hand.

With the above and other objects and advantages in view, the invention resides more 35 particularly in the novel combination, formation and arrangement of parts herein-after described and particularly pointed out in the appended claims.

In the accompanying drawings:

40 Figure 1 is a plan view of the front of a hand constructed in accordance with the present invention, portions of the glove being broken away.

45 Fig. 2 is a similar view of the back of the hand.

Fig. 3 is a longitudinal sectional view through the hand on the line 3-3 of Fig. 2.

Fig. 4 is an enlarged transverse sectional view through one of the finger members.

50 Fig. 5 is a sectional view taken transversely through the base portion of the thumb.

55 Referring now more particularly to the accompanying drawings, the improved artificial hand comprises a body block 10, simi-

lar in shape to the palm of a natural hand, and threaded in the wrist end of the body block and passed through a plate 11 secured to said wrist end is an attaching bolt 12 adapted for securement to the body of the 60 artificial arm portion in a conventional manner. The plate 11, which is preferably of aluminum, is provided with an inturned annular binding flange 13 surrounding the body block. At the finger end of the body 65 block there are provided a plurality of extensions 14 corresponding to the fingers and each outwardly tapered to an edge extending transversely of the hand. Each of the fingers is formed of a core member 15 of 70 very stiff wire extending into and anchored in the body member and surrounding the core wire is a sheathing formed of a plurality of thicknesses of rubberized fabric 16 on which is molded a finger body 17 of rubber or similar resilient material, and the base of each finger body is provided with a V-shaped recess to receive the corresponding finger projection 14 and anchor nails 18 are driven obliquely through the base portions 80 of the finger bodies and into the projections 14. Surrounding the junctures of the finger bodies and the body block 10 is a band of metal 19, preferably of aluminum and inset in the body block and finger bodies, the edge 85 portions of the band where it overlaps the finger bodies 14 being slit at 19^A whereby the metal may be bent between and against the finger bodies.

A comparatively simple and exceedingly 90 strong and durable means is thus provided for anchoring the finger members to the body of the hand, to lessen the strain on said finger members at their junctures with the hand and to avoid a possible appearance of 95 a seam at said junctures.

For attaching a thumb member to the palm body block 10, the corresponding portion of the body block is provided with a projection 20 shaped to form itself a thumb 100 base portion, and tapered at its outer end for the engagement of the recessed inner portion of a thumb body 21 molded on a rubberized fabric sheathing 22 in which is disposed, as described in conjunction with the 105 finger members, a stiff core wire 23 embedded in the body block. Embedded in and shaped to fit that portion of the body block 10 surrounding the thumb base 20 thereof is a plate 24, from which extends a 110

collar 25 overlapping the juncture of the thumb base 20 and the rubber thumb body 21.

The entire hand thus provided is covered by a leather sheathing or glove 26, to cover the junctures of the various portions of the hand and impart a natural appearance thereto. The core wires of the thumb and fingers are of such strength preferably as to resist a bending pressure up to twenty-five pounds, and they may be readily bent to any desired natural positions, or may be bent to embrace and hold an object.

What is claimed is:

- 15 1. An artificial hand comprising a base block, finger and thumb core wires extending from and secured in the base block, pliable finger and thumb body members surrounding said core wires, metallic bands surrounding the junctures of the finger and thumb body members with the body block and a sheathing for the finger and thumb member and the body block.
- 20 2. An artificial hand including a palm body block, finger core wires extending from and secured in the body block, pliable finger bodies surrounding the core wires, a metallic band surrounding the junctures of the

finger bodies and body block, and the outer portion of said band being slit and the metal between said slits being bent about the base portions of the finger body.

3. An artificial hand including a palm body block, a plurality of beveled extensions on said body block, pliable finger bodies recessed to fit about said extensions at their base portions, and secured to said extensions, stiffening wires extending through said finger bodies and embedded in the body block and a sheathing for said finger members 40 and body block.

4. An artificial hand including a palm body block, an extension on said body block forming a thumb base portion, a plate fitted against the body block about said thumb base portion, a pliable thumb body secured to said thumb base portion and a collar on the plate embracing the thumb base portion and the adjacent portion of the thumb body.

In testimony whereof, we affix our signatures, in the presence of two witnesses.

GAVIN RALSTON.
EARL BLANKENSHIP.
